UNITED STATES PATENT OFFICE.

PETER J. LAYMAN, OF AKRON, OHIO, ASSIGNOR TO FRANK X. ADAMS, OF AKRON, OHIO.

JAR-CLOSURE.

No. 884,826.

Specification of Letters Patent.

Patented April 14, 1908.

Application filed November 1, 1906, Serial No. 341,597. Renewed October 30, 1907. Serial No. 399,787.

To all whom it may concern:

Be it known that I, PETER J. LAYMAN, a citizen of the United States of America, residing at Akron, in the county of Summit 5 and State of Ohio, have invented certain new and useful Improvements in Jar-Closures, of which the following is a specification, reference being had therein to the accompanying drawing.

10 This invention relates to receptacle closures, and the invention relates more particularly to a closure designed for jars, as fruit and milk jars.

15 The invention has for its primary object to provide a simple and inexpensive closure, wherein positive and reliable means are employed for locking a cap or similar closure in engagement with a jar.

20 Another object of this invention is to dispense with the use of corks and stopper clasps heretofore used for closing small receptacles.

To this end, I construct a jar or similar receptacle with an annular flange adapted to support a cap and with inwardly projecting 25 lugs adapted to lock a washer upon said cap, said washer being constructed whereby when it is placed in engagement with a jar or similar receptacle, the cap will be firmly held upon the annular flange of said receptacle, 30 thus insuring a positive closure of said receptacle.

The detail construction of my improved closure will be presently described and then specifically pointed out in the claims, and referring to the drawing forming part of this 35 specification, like numerals of reference designate corresponding parts throughout the several views, in which:—

Figure 1 is a vertical sectional view of a 40 jar equipped with my improved closure, Fig. 2 is a front elevation of a wrench employed for opening the jar, Fig. 3 is a side elevation of the same, Fig. 4 is a plan of a closure-disk constituting one of the elements of 45 the closure, Fig. 5 is a plan of my improved closure, as applied to a jar, Fig. 6 is a side elevation of the closure-disk, Fig. 7 is a similar view of a modified form of closure-disk, Fig. 8 is a perspective view of the securing 50 washer which locks the closure disk in position in the holder or receptacle. Fig. 9 is a plan view of a modified construction in which the closure-disk and washer are integral.

55 To put my invention into practice, I construct the opening or neck end 1 of a jar or

similar receptacle with an interior annular shoulder or flange 2, located a slight distance below the upper end of the receptacle, and at the upper end with inwardly extending 60 equally spaced lugs 3, said lugs being segment-shaped and occupying approximately one-half the circumference of the jar or receptacle.

Upon the annular shoulder 2 is adapted to 65 rest a closure-disk 4 having a depending portion 5 fitting snugly within the inner wall of the flange 2 and an upwardly extending circular portion 6. The closure disk may, if desired, have a washer or gasket 5' surrounding 70 the depending portion 5 as shown in Fig. 1, to effect a close union with the flange 2. After the closure-disk is placed upon the shoulder 2 of the jar or receptacle, a washer 7 is placed over the portion 6 of the closure-disk, said washer having radially disposed 75 lugs 8 corresponding to the spaces 9 formed between the lugs 3 of the jar or receptacle. The lugs 8 are formed with beveled ends 10, and said washer is provided with diametrically opposed openings 11, whereby a wrench 12 can be placed in the openings 11 to rotate 80 said washer and cause the lugs 8 to ride along under the lugs 3 of the jar or receptacle. The beveled ends 10 of the lugs when being forced 85 under the lugs 3 cause the washer 7 to seat firmly upon the closure-disk 4, and thereby force said closure-disk downwardly upon the shoulder 2 insuring a non-leakable closure 90 for the jar or receptacle.

The wrench 12 which I use in connection 95 with the washer 7 is preferably constructed of a piece of wire, bent to provide depending ends 14 adapted to fit within the openings 11 of the washer 7, and twisted to form a handle 15, whereby the wrench can be easily and quickly manipulated to remove the washer from the jar or receptacle.

In Fig. 7 of the drawings, I have illustrated a modified form of closure-disk 4^a wherein the 100 edges of the disk are beveled as at 4^b to insure a more positive closure of the jar or receptacle, while in Fig. 8 of the drawings, I have illustrated a further modification of the invention, in which the closure-disk 7^a and washer 7^b 105 are made integral, this construction being particularly adapted for bottles and similar small receptacles. To insure a positive connection between a jar and the device illustrated in Fig. 8, a gasket of rubber or cork 110 (not shown) can be readily used.

I do not care to confine myself to the type

of jar or receptacle in connection with which my improved closure is used, or to the size, proportion or minor details of the same.

What I claim and desire to secure by Letters Patent, is:—

- 5 1. In combination with a jar having an interior annular shoulder, and inwardly-projecting lugs carried by said jar above said shoulder, a closure-disk adapted to rest on the shoulder and having a circular depending portion fitting with the circular inner wall of said shoulder, and a washer engaging the closure-disk having a plurality of radially-disposed peripheral-lugs adapted to take under and engage with the lugs of the jar.
- 10 2. In combination with a jar having an interior annular shoulder, and inwardly-pro-

jecting lugs on the inner face of the jar above said shoulder, a closure-disk resting on the said shoulder and having a depending circular portion fitting with the inner wall of the shoulder, a washer engaging the closure-disk and having diametrically-opposed wrench-receiving openings, and peripheral-lugs carried by said washer to take under and engage 25 with the lugs in the jar, each lug on the washer having a beveled end, as and for the purpose described.

In testimony whereof I affix my signature in the presence of two witnesses.

PETER J. LAYMAN.
